COMBINATION ILLUMINATING AND
STERILIZING LAMP

Maxwell M. Bilofsky, Newark, N. J.

Application August 20, 1943, Serial No. 499,396

1 Claim. (Cl. 240—51.11)

1

The present invention relates to combined illuminating and sterilizing units.

A vapor electric sterilizing lamp that generates and transmits strong actinic rays is highly injurious to the human eye and so is not useful for illumination. Since the glass tube of the ordinary vapor electric lamp intercepts such actinic rays, such lamp is without utility for sterilization.

It is among the objects of the present invention to combine in a single unit the utilities of a vapor electric illuminating lamp and of a vapor electric sterilizing lamp, with complete efficacy of the lamp for illumination and for sterilization and without jeopardy to the eye-sight of the person looking at the lamp while in use.

Another object is to attain the foregoing objectives without resort to highly specialized, unconventional, complicated and costly constructions that require specialized mounting and terminal equipment, but on the contrary to attain the combined result by resort to a vapor electric lamp unit of substantially conventional external appearance with substantially conventional filaments and terminals and of substantially conventional size and shape of tube.

In the accompanying drawings in which is shown one or more of various possible embodiments of the several features of the invention,

Fig. 1 is a more or less diagrammatic view showing the combined illuminating and sterilizing lamp and fixture combination as installed.

Fig. 2 is a cross-sectional view transversely through Fig. 1, and

Fig. 3 is a cross-sectional view of another embodiment of the lamp unit per se.

Referring now to Fig. 1, the lamp of conventional appearance may include a cylindrical tube T having end disks or plugs 10 and 11 and having a pair of terminal prongs 12 at one end connected by the filament 13 and a like pair of terminal prongs 14 at the opposite end connected by the filament 15. The filaments are covered with thermionic material, such as barium oxide and the chamber is filled with low pressure gas, preferably noble gas, and with a small amount of mercury. The inside of the transparent tube T is coated with the usual fluorescent paint 16.

According to the invention, the transparent tube T is of composite construction. A continuous trough-shaped portion 17, extending from end to end of the tube T, is of the type of glass customary for lighting, ordinarily of lead or lime glass, which, while transparent to the luminous rays, is substantially impervious to the actinic

rays or ultra-violet rays shorter than those in the visible spectrum.

The remainder of the transparent tube, that is, the section or strip 18 thereof intervening between the edges 19 and 20 of the plain glass section 17 is desirably also trough-shaped and is of suitable material, which is substantially transparent to the ultra violet or short wave, actinic or sterilizing rays. Section 18 may be of quartz, but is preferably of specialized glass transparent to ultra violet or sterilizing rays. One familiar type of such glass is characterized by containing about two per cent of boric oxide and having low iron oxide and titanium oxide content. The section 18, desirably of the same thickness as section 17, is bonded at its lateral edges as a unitary and integral part of the plain glass section 17, preferably by autogenous bonding or fusing of the sections under heat as at 19 and 20. Desirably the edges of contact between the plain and the ultra violet glass sections extend radially of the tube, as shown, for promoting facility of assembly.

The sterilizing section 18 should be so arranged that it is behind the plain glass section in use, in order to assure protection to the persons exposed to the lamp.

By way of example, the complementary sections 17 and 18 may extend each for half the periphery of the tube, but ordinarily the plain glass section will extend along a greater arc than the ultra violet glass section. The ultra violet glass section 18 is illustratively shown as of 60 degree width in Fig. 2 and such section 18' as of 90 degree width in Fig. 3. In Fig. 3 the reference numerals for corresponding parts are the primed numerals of Fig. 2.

In a preferred installation, the lamp is mounted in a fixture which may be conventional and presents spaced sockets 22 for the terminal prongs 12 and 14. The sockets 22 are of the conventional construction in which the pair of prongs at each end of the lamp are not in the plane of the sheet as shown, but in a plane perpendicular thereto.

The fixture is equipped with a reflector 23 which may be continuous and conventional. Preferably, however, it departs somewhat from the conventional in that its mid-section is open at 24 for the length of the reflector and desirably has inturned flanges 25 substantially registering with the lateral edges of the sterilizing section 18.

Thus, in use of the lamp, with the reflector as customary either behind or above the luminous unit, the sterilizing section 18 is always behind the glass section 17 so that the actinic rays that pass through said sterilizing section 18 will not

reach the eyes of the persons near the fixture. The actinic rays pass through the opening 24 of the reflector to perform their sterilizing effect and are dissipated by the wall above or behind, so that they cannot possibly do injury to the eyes of the persons in the room.

It will be understood that the invention is not limited to the use of any particular type of vapor electric lamp but may be incorporated in structures of either the hot cathode type illustratively shown, or the cold cathode type, it being merely important that the luminous vapor emit potent actinic rays. It will also be understood of course that the invention could be carried out in a structure generally of the type of the prior Patent No. 2,298,336, issued October 13, 1942, on application of Maynard A. Babb, in which the unit is mounted from one end only.

Changes could be made in the above construction and different embodiments of this invention could be made without departing from the scope of the claim. It is intended that all matter contained in the above description or shown in the accompanying drawing shall be interpreted as illustrative and not in a limiting sense except to the extent that such limitations are imposed by the appended claim.

Having thus described my invention, what I claim as new and desire to secure by Letters Patent is:

A combined lighting and sterilizing fixture comprising a terminal and carrier structure for a vapor electric lamp, a vapor electric lamp carried therein and having disks at the opposite ends thereof, electrodes carried thereby, said lamp having a tubular casing, the entire length of which for the major portion of the peripheral area thereof being of glass characterized by substan-

tial imperviousness to the ultra violet rays generated in the lamp and transparency to visible rays, said glass portion extending along substantially that area of the lamp which in the installed fixture is directly exposed to view, the remaining area of the lamp tube, that is, the portion which in the installed fixture is behind said glass portion being of ultra violet glass and being bonded as a unitary portion with the edges of the glass portion, said fixture including a reflector for projecting the light through the first glass portion to the field of vision, said reflector presenting a passageway therethrough concealed from view by the lamp and having radiating walls the length thereof registering with the lateral edges of the ultra violet glass portion for permitting the sterilizing action without injury to the eyes.
